(57) **CLAIM**

I claim the ornamental design for a pneumatic distributor, as shown and described.

DESCRIPTION

FIG. 1 is a top left perspective view of a pneumatic distributor in accordance with my new design;

FIG. 2 is a bottom left perspective view thereof;

FIG. 3 is a bottom right perspective view thereof.

FIG. 4 is a bottom view thereof;

FIG. 5 is a top plan view thereof;

FIG. 6 is a left view thereof; and,

FIG. 7 is a right view thereof.

The dashed lines illustrate portions of the distributor that form no part of the claimed design.
